UNITED STATES PATENT OFFICE.

WILLIAM LEUCKERT, OF ASTORIA, NEW YORK.

COMBINATION LAMP AND MIRROR.

1,412,690.

Specification of Letters Patent. Patented Apr. 11, 1922.

Application filed March 11, 1920. Serial No. 364,886.

To all whom it may concern:

Be it known that I, WILLIAM LEUCKERT, a citizen of the United States, residing at Astoria, county of Queens, and State of New York, have invented certain new and useful Improvements in Combination Lamps and Mirrors, of which the following is a specification.

This invention relates to a combined mirror and lamp holder for automobiles, the present invention being an improvement over that disclosed in a previous patent granted to me on July 1st, 1919, No. 1,308,182.

The present improvement has for an object to provide a novel arrangement whereby the electric current to the lamp is automatically switched on or off as the mirror is adjusted from operative to inoperative position or vice versa.

For further comprehension of the invention, and of the objects and advantages thereof, reference will be had to the following description and accompanying drawings, and to the appended claims in which the various novel features of the invention are more particularly set forth.

Figure 1 of the drawings is a perspective view showing the device mounted on the wind-shield of an automobile.

Figure 2 is an axial sectional view of the device.

Figure 3 is a transverse section on the line 3—3 of Figure 2.

Figure 4 is a side view of the lamp mounting.

Figure 5 is a transverse section on the line 5—5 of Figure 2.

Figure 6 is a side elevation of a modified form of the device, showing it mounted on the mud guard of an automobile.

Figure 7 is an axial sectional view of this modification.

Figure 8 is a transverse section on the line 8—8 of Figure 7.

Figure 9 is a transverse section on the line 9—9 of Figure 7.

In Figure 1 of the drawings 1 indicates a portion of the windshield of an automobile and 2, the side frame post of the windshield. As shown in the drawings a hollow globular head 3 has projecting from one side thereof a sleeve 4, the end of which is thickened as at 5, a pair of clamp ears 6 extending from this thickened part, the tube being slotted longitudinally from the end for a distance as at 8 to permit of contraction by a screw

9 engaging the clamp ears in a well known manner.

Extending into the sleeve 4 is a tube 10 which has formed integral with the end 60 thereof a split clamp element 11 which cooperates with a second split clamp element 12 to fix this tube, and with it the device, on the post 2. The clamp element 12 is fastened in place by means of screws 13 passing through a flange 11' on the other clamp element and screwed into a flange 12' thereon. The wall of the tube 10 at the end adjacent the clamp element is preferably thickened as at 10'. To hold the sleeve 4 against longitudinal movement on the tube 10 a screw 15 is threaded through the thickened end 10' of the latter and projects into a quadrantal slot 16 in the tube.

The globular head 3 has fixed to one side thereof a mirror 18 of any suitable construction and has mounted therein an electric lamp 19 to be presently further referred to. The mirror 18 is preferably arranged to have angular adjustment on the head 3, the mirror 30 having a screw 20 projecting axially from the back thereof through a relatively large opening 21 in the head. A washer 23, having its outer face convexed in conformity to the curvature of the head 3, is placed over the screw 20 and a nut 24 is threaded on the screw and thereby clamps the mirror in place. To permit of access to the nut 24, the head 3 has an opening on the opposite side in axial alignment with the opening 21 35 and normally closed by a screw cap 25, the nut having a slot 26 for engagement by a screw driver or the like.

The lamp 19 is preferably located at the center of the head 3 which latter has a pair 65 of openings such as 30 formed on opposite sides thereof at right angles to the axial line of the mirror 18, these openings being closed by screw rings 31 carrying lenses 32 and 33 the lens 32 being a red lens, and the lens 33 a white lens.

The means whereby rotation of the head 3, carrying with it the mirror and lenses causes the circuit to the lamp to be opened or closed is as follows:—The lamp is mounted on a plug 35 or ordinary type and having a pair of spaced contacts 36 at its end. This plug is mounted in the inner end of a short cylinder 37, being held in place in a well known manner against rotation, and outward displacement by studs 38 thereon engaging in slots 39 in the cylinder.

Mounted in the outer end of the cylinder 37, is an insulating base 40 containing a pair of contact tips 41 resiliently pressed in a well known manner toward the plug 35. 5 These tips are adapted to engage the contacts 36 when the head is moved to put the mirror in operative position and move away from the same when the head is moved to turn the mirror away from operative position. 10

To cause the relative movement of the plug 35 and base 40 necessary to this operation the cylinder 37 is fixed to the sleeve 4 to rotate therewith while the base 40 is fixed 15 to the tube 10 to be held against rotation thereby. To this end a screw 43 is passed through a suitable close fitting aperture in the sleeve 4 and is threaded into the cylinder 37, while a screw 44 passes from the tube 20 through a quadrantal slot 45 in the cylinder 37 and is threaded into the base 40.

It will be apparent then that when the head 3 is rotated it carries with it the cylinder 37, which in turn carries the lamp plug 25 35 with its contacts 36, while the screw 44 holds the base 40 against rotation, the quadrantal slot 45 in the cylinder permitting rotation of the latter as will be obvious. I prefer to arrange the parts so that when the 30 mirror is mounted facing backward the lamp circuit will be open and will be closed by swinging the mirror to the downwardly facing position shown in Figure 2 in which the red lens 32 faces toward the rear and the 35 white lens faces toward the front.

In the modified form shown in Figures 6 to 9, the principle of operation above described is maintained, the device being arranged for mounting on the mudguard of the 40 front wheel, the mud guard being indicated in cross section at 50. In this modification the globular head 3', mirror 18', red and white lenses 32' and 33' are as above described. Fixed to the underside of the 45 globular head 3', is a short sleeve 51 which projects into a hollow standard 52 having a widened base 53 adapted to be secured by screws 54 to the mud guard of the automobile. The opening 55 through the base into 50 the standard is of diminished size and is surrounded by an upstanding flange 56 spaced inwardly from the wall of the standard.

Fitting snugly over this flange and resting upon the base is a tube 57 whose upper end projects into the sleeve 51 this tube being held against rotation by a pin 58 on the flange which projects into a longitudinal slot 59 in the lower end of the tube, this 60 tube corresponding in junction to the tube 10 and enclosing at its upper end a cylinder 37' similar to the cylinder 37, this cylinder containing a lamp plug 35' with its terminals, and base 40' with its terminals in all 65 respects similar to those shown in Figures 2

and 4. The cylinder 37' is fixed to the sleeve 51 by a screw 43' similar to the screw 43, while the base 40' is fixed to the tube 57 by a screw 44' similar to the screw 44 and passing through a like quadrantal slot in 70 the cylinder. The sleeve 51 is retained against longitudinal displacement from the standard 52 by means of a screw 60 threaded through the latter and projecting into a quadrantal slot 61 in the sleeve, while a 75 clamping device 62, similar to that shown in Figure 1 is carried on the end of the standard to clamp it tightly upon the sleeve when desired.

It will be apparent that rotation of the 80 head 3' will cause the cylinder 37' and lamp plug to rotate and thereby close or open the lamp circuit, the parts being arranged that a turn of the mirror from a backward facing position to a position facing inwardly 85 toward the engine hood will close the circuit and vice versa.

Having thus described my invention what I claim as new and desire to protect by Letters Patent of the United States is as follows: 90

1. In a device of the class described, a hollow head, a lamp in said head, said head having an aperture for exposure of said lamp, a mirror carried by said head, an element on which said head is rotatably mounted, a lamp plug rotatable with said head, a contact device non-rotatable on said element and adapted to engage the said lamp plug and close the circuit to the lamp when 100 the said plug and device are in one relative rotative position and to open the lamp circuit when the said plug and device are in another relative rotative position.

2. In a device of the class described, a hollow head, a lamp in said head, said head having an aperture for exposure of said lamp, a mirror carried by said head, an element on which said head is rotatably mounted, a lamp plug rotatable with said head, a contact device non-rotatable on said element and adapted to engage the said lamp plug and close the circuit to the lamp when the 110 said plug and device are in one relative rotative position and to open the lamp circuit 115 when the said plug and device are in another relative rotative position, and means limiting the relative rotation of said lamp and device between the said positions.

3. In a device of the class described, a hollow head, a mirror carried by said head, lamp lenses carried by said head, a sleeve projecting from one side of said head, a tube projecting into said sleeve, a cylinder engaged by the outer end of the sleeve, a lamp plug and a contact base spaced longitudinally in said cylinder, contact elements on said plug and base adapted to engage and disengage as said plug is rotated relatively to said base, said plug being non-rotatable in 125 130

said cylinder and said base being rotatable in said cylinder, a screw passing from the said sleeve to the cylinder and fixing the latter to the former to rotate therewith, and 5 a screw passing from the said tube to the said base and fixing the latter to the former, said cylinder having a quadrantal slot in the wall thereof through which said last screw passes.

10 4. In a device of the class described, a hollow head, a lamp in said head, said head having an aperture for exposure of said lamp, a mirror carried by said head, an ele-

ment on which said head is rotatably mounted, a lamp plug carried in said head to 15 rotate therewith, and a contact making device carried by and enclosed within the said element and adapted to engage the said lamp plug and close the circuit to the lamp when the said plug and device are in one relative 20 position and to open the lamp circuit when the said plug and device are in another relative position.

In testimony whereof I have affixed my signature.

WILLIAM LEUCKERT.
